UNITED STATES PATENT OFFICE.

ORLANDO J. SMITH, OF NEW YORK, N. Y., ASSIGNOR TO THE AMERICAN PRESS ASSOCIATION, OF SAME PLACE.

PRINTING-SHELL.

SPECIFICATION forming part of Letters Patent No. 365,352, dated June 21, 1887.

Application filed June 13, 1885. Serial No. 168,600. (No model.)

To all whom it may concern:

Be it known that I, ORLANDO J. SMITH, a citizen of the United States, residing at New York, in the county of New York and State of New York, have invented certain new and useful Improvements in Electrotype Printing-Shells; and I do hereby declare the following to be a full, clear, and exact description of the invention, such as will enable others skilled in the art to which it appertains to make and use the same.

My invention consists in the combination, with an electrotype or stereotype plate, of a flexible sheet or strip adhesively attached to the under surface of the plate, and having flaps extending laterally beyond the edges of the plate to hold the plate to the base-block.

Figure 1 is a perspective view of an electrotype-shell secured to a plate of flexible metal. Fig. 2 is a rear view of the same, the dotted lines indicating where the plate is to be bent to form the flanges. Fig. 3 is a perspective view of a shell secured to a plate of flexible metal mounted on a base-block, with the holding-flanges bent at a right angle.

Referring to the drawings, A represents an electrotype - shell secured by any suitable means, but preferably by solder, to a rectangular plate, B, of flexible metal—such as sheet tin, copper, zinc, or other analogous material. This plate corresponds in length with the shell to which it is to be secured; but its width is somewhat greater than that of the shell, in order to form holding-flanges b on either side.

C is a base-block on which to mount the shell. This block is of such height as to raise the face of the shell type-high.

In locking the shell in the form, it is first laid on the base-block, and then flanges b are bent downward at a right angle. When the column-rules are placed in position, they will

of course bear against the flanges and hold them, when the form is locked up, firmly to the base-block.

I am aware of Patent No. 146,454, granted 45 to Marshall J. Hughes, dated January 13, 1874, in which is shown a reversible stereotype plate provided with a lining or lateral extension of sheet metal to facilitate locking up the same. I am also aware of the patent to Albert W. 50 Marshall, No. 312,596, dated February 17, 1885, wherein is shown an electrotype-shell made of flexible metal without the usual metal backing, and provided with sides extending out beyond the line of the printing-surface to 55 form flanges. My invention differs from both of these patented devices, in that by securing a flexible metal plate to the flexible shell I provide a backing and holding-flanges for it, and at the same time preserve its flexibility. 60 Hughes' flexible plate lies between two rigid printing-surfaces—that is to say, it is in the center of a reversible stereotype-plate. Marshall's shell is not provided with a backing, and the holding-flanges are integral with the 65 shell and are necessarily of the same material.

Having thus described my invention, what I claim as new, and desire to secure by Letters Patent, is—

The combination, with an electrotype or 70 stereotype plate, of the flexible sheet or strip adhesively attached to the under surface of the plate, and having flaps extending laterally beyond the edges of the plate to hold the plate to the base-block, substantially as described. 75

In testimony whereof I affix my signature in presence of two witnesses.

ORLANDO J. SMITH.
